DESIGN FOR A GARMENT HANGER

John Bolten, Andover, Mass., and Henry Spitz,
Great Neck, N. Y.

Application December 19, 1945, Serial No. 124,875

Term of patent 7 years

(Cl. D80—8)

To all whom it may concern:

Be it known that we, John Bolten and Henry Spitz, citizens of the United States, residing respectively at Andover, county of Essex, State of Massachusetts, and at Great Neck, county of Nassau, State of New York, have invented a new, original, and ornamental Design for a Garment Hanger, of which the following is a specification, reference being had to the accompanying drawing, forming part thereof, wherein,

Fig. 1 is a side elevational view of a garment hanger showing our new design, and

Fig. 2 is a vertical sectional view thereof taken on line 2—2 of Fig. 1 and looking in the direction of the arrows.

We claim:

The ornamental design for a garment hanger, substantially as shown.

JOHN BOLTEN.
HENRY SPITZ.
